NOISEMAKING NOVELTY DEVICE

James F. La John, Erie, Pa.

Application June 6, 1951, Serial No. 230,158

6 Claims. (Cl. 272—27)

1

This invention relates generally to a noise making amusement device and more particularly to a noise making novelty simulating the outward appearance of a conventional cigarette lighter.

Novelty noise making devices utilizing percussion caps are usually operable upon the opening of a cover or the like, thereby exposing the exploding percussion cap with the result that flying particles from the cap cause damage to clothing and they get into the eyes or onto the skin of the persons close to the device, thereby resulting in injury to their person. These devices usually operate upon the opening of a cover or the like which is held down towards the middle of the body a good distance from the ears of the person operating the novelty device so that the elements of surprise is not as complete as when one is waiting for a light from a conventional cigarette lighter poised in front of a cigarette in his mouth. A percussion cap exploding in the air does not make a very loud noise as compared to one which explodes in an enclosure.

It is the principal object of my invention to provide a noise making novelty having the same outward appearance as a cigarette lighter which is simple in construction, economical in cost, economical in manufacture, and efficient in operation.

Another object of my invention is to provide a noise making novelty which may utilize the outer case of a conventional cigarette lighter.

Another object of my invention is to provide an explosive noise making novelty enclosed so that a comparatively loud report is obtained from a comparatively small explosive cap.

Another object of my invention is to provide a noise making novelty which is so deceptive and positioned in such a manner as to provide the greatest element of surprise to an unsuspecting user of the device.

Another object of my invention is to provide a noise making novelty which provides simple means for placing the cap therein in position for operation.

Another object of my invention is to provide a device for exploding an explosive cap in absolute safety.

Other objects of my invention will become evident from the following detailed description, taken in conjunction with the accompanying drawings, in which

Fig. 1 is a side elevational view of my novel noise making novelty simulating the outward appearance of a cigarette lighter;

Fig. 2 is a vertical sectional view through the insert member containing my novel mechanism for exploding a cap, the mechanism being in a retracted position; and

Fig. 3 is a vertical sectional view through the insert member of my novel noise making novelty

2

wherein the hammer urged by the spring has been released to engage the cap therein.

Referring now to the drawings, I show in Fig. 1 a conventional rectangular shaped outer case 1 having a cover 2 hinged at 3 and a spring 4 engageable with a cam portion 5 on the cover 2 to urge the cover 2 to an open or a closed position. This type of case is now used on conventional nationally advertised lighters.

10 An insert member 9 fits into the case 1 as shown in Fig. 1 and it comprises an insert case 10 open at the bottom thereof. It has a perforated oval shaped shield 11 mounted on the upper end thereof with a simulated wick 12 extending upwardly therein. The shield 11 has laterally directed ears 13 with vertically extending slots 14 to receive a screw shaft 15 carrying a knurled wheel 16, the knurled wheel 16 simulating the conventional knurled friction wheel on conventional lighters now on the market. The insert case 10, the oval shaped shield 11, the wick 12, and the knurled wheel 16 are exactly the same in shape and size as similar elements on cigarette lighters now on the market. A vertically extending shaft 17 is attached to the underside of the knurled wheel 16 and it extends downwardly through a depending tubular portion 18 inside the insert case 10 through which flints are usually extended in a conventional lighter. The shaft 17 has the lower end 19 thereof threaded to threadably receive threaded nuts 20 and 21. A hook member 22 is disposed and secured between the nuts 20 and 21. The insert case 10 has a transverse shaft 23 mounted therein upon which is mounted the intermediate looped portion 24 of a spring member 25. One end 26 of the spring member 25 abuts against the depending tubular member 18 and the opposite end 27 thereof has a hammer 28 mounted thereon adapted to strike 30 the head 29 of a percussion cap disposed on the lower inner side of the case 10 as shown in Figs. 2 and 3. The hammer 28 has a peripheral groove 30 engageable by the end of the hook 22 to hold the hammer 28 in a retracted position as shown in Fig. 2. The shaft 17 is urged upwardly by the spring 31 which is disposed between the underside of the wheel 16 and the top of the insert case 10. The spring 31, therefore, urges the end of the hook 22 into engagement with the groove 30 in the hammer 28 as shown in Fig. 2.

In the operation of my novel noise making novelty, the hammer 28 is retracted by the forefinger to a position as shown in Fig. 2 and the shaft 17 is forced downwardly by pressing a finger against the wheel 16 to a position where the end of the hook 22 engages the groove 30 whereby the wheel 16 is released and the shaft 17 moves upwardly to hold the hammer 28 in a retracted position as shown in Fig. 2. The cap is then disposed on the lower inner side of

the insert case 10 as shown in Fig. 2. A thin plate to form an anvil may be disposed at this point in the insert case 10 to place a percussion cap thereon although it is not necessary for the successful operation of my novelty device. The insert member 9 is then inserted in the outer case 1 as shown in Fig. 1, thereby simulating the outward appearance of a conventional cigarette lighter. The lighter is handed to an unsuspecting person who desires a light for his cigarette or cigar whereupon he places his finger on the wheel 16 to rotate it in the usual manner with the result that the shaft 15 is moved downwardly in the slot 14, thereby moving the shaft 17 downwardly to push the end of the hook 22 out of engagement with the groove 30 in the hammer 28 whereby the hammer 28 is released and snapped by the spring 25 against the percussion cap 29 to cause a loud report. The explosion of the cap is absolutely safe because it is inside of the outer case 1 and also the insert case 10, thereby enclosing all flying particles from the cap within the cases 1 and 10. The enclosed cases 1 and 10 also tend to greatly amplify the sound from the cap.

It will be evident from the foregoing description that I have provided a novel noise making novelty which exactly simulates the outer appearance of a conventional cigarette lighter now on the market, one which is safe, one which amplifies the sound of a percussion cap, one which is deceptive and does not arouse suspicion as to what is in the device, one which is very simple in manufacture, and one which is easily operated by an unsuspecting person without the detection of any trick of any kind.

Various changes may be made in the specific embodiment of my invention without departing from the spirit thereof or from the scope of the appended claims.

What I claim is:

1. A noise making novelty device comprising an outer case having a cover, an insert case for disposal in said outer case having a simulated shield and knurled wheel, a shaft attached to said wheel and extending downwardly into said insert case, a spring for urging said shaft upwardly, a hook carried on the lower end of said shaft, a spring urged hammer mounted in said insert case adapted to be held by said hook in a retracted position, and means for disposing a cap in said insert case adapted to be struck by said hammer, said hammer being released by said hook upon longitudinal movement of said shaft.

2. A noise making novelty device for disposal in a conventional cigarette case comprising an insert casing open at the bottom thereof and having a simulated shield and wick and a knurled wheel supported thereon, a shaft attached to said wheel and extending downwardly in said insert casing, a spring for urging said shaft upwardly, a hook attached to the lower end of said shaft, a spring disposed in said insert casing, a hammer attached to said spring adapted to be engaged by said hook for holding it in a retracted position, and means in said casing for placing an explosive cap in the path of said hammer for explosion thereby, said hook being disengaged from said hammer upon longitudinal movement of said shaft in said insert casing.

3. A noise making novelty device simulating the outer case and insert case of a conventional cigarette lighter comprising an outer casing, an

insert casing for disposal in said outer casing, a knurled wheel on said insert casing, a shaft connected to said wheel and extending internally of said insert casing, a coil spring surrounding said shaft between said insert casing and said wheel, a hook member carried by said shaft in said insert casing, a spring urged hammer in said insert casing adapted to be held in a retracted position by said hook member, and means for positioning an explosive cap in said casing in the path of said hammer to explode same, said hammer being released upon pressure being applied longitudinally of said shaft on said knurled wheel whereby said shaft is moved longitudinally.

15 4. A noise making novelty device as set forth in claim 3 wherein said spring urged hammer is supported by a V-shaped spring supported intermediate thereof on a transverse shaft in said insert casing, one end of said spring having said hammer attached thereto and the other end of said spring being anchored in said insert casing.

5 5. A noise making novelty device simulating the outward appearance of a cigarette lighter and insertable in a conventional cigarette lighter

25 case comprising an insert casing, a knurled wheel simulating the friction wheel of a cigarette lighter disposed on the end of said casing, a shaft attached to said wheel and supporting same extending into said insert casing, a coil spring surrounding said shaft between the end of said casing and said wheel, a hammer in said casing, a spring for supporting said hammer and urging it towards one side of said casing, a catch on the lower end of said shaft for releasably securing said hammer in a retracted position, means for releasing said hammer upon longitudinal movement of said knurled wheel and shaft supporting the same, and means for positioning an explosive cap in said casing in the path of said

30 hammer so that it may be exploded by same.

40 6. A noise making novelty device simulating the outward appearance of an outer cigarette lighter case and an insert case disposable therein comprising an outer case, a cover on said case, an insert case for disposal in said outer case, a simulated guard, wick, and knurled wheel on one end of said insert case, a shaft connected to said knurled wheel and extending into said insert case, a spring for urging said shaft and knurled wheel outwardly from said insert case, a connecting link carried on the lower end of said shaft, a hammer disposed in said insert case, a spring member in said case to force said hammer towards one side of said case, and means for positioning an explosive cap on one side of said case in the path of said hammer, said connecting link on said shaft being adapted to hold said hammer in a retracted position and being adapted to release same upon longitudinal movement of said shaft.
